9 Claims. (Cl. 53—64)

This invention relates to apparatus for depositing filled paper cartons or containers, such as those employed for containing milk and other liquids, into crates or cases. This application is a continuation-in-part of application Serial No. 602,885, filed August 8, 1956.

The objects of the original application were as follows:

A carton or paper container particularly adapted for handling by the described apparatus is one which may be provided at the top with a centrally positioned upstanding flange. In the described apparatus, means are provided for grippingly engaging a plurality of the cartons by these flanges and holding them suspended, and lowering the cartons thus suspended down into crates located in position to receive them, and then releasing the cartons.

It is one of the objects of the invention to provide an apparatus, operative as above described, for speedily and accurately handling the filled cartons or containers and depositing a predetermined number of the cartons in an upright position in each crate.

It is an object of the invention to provide means by which a predetermined number of the filled cartons will be deposited in an upright position in each of the crates.

In presenting the new subject matter forming the basis for this continuation-in-part application, certain additional objects are intended. These objects are as follows:

Another object of the invention is the provision of means which will compact the suspended cartons together and prevent bulging thereof at the time of their suspended introduction into an awaiting case.

Another object is the provision in a carton gripping head of means for compacting together a group of cartons gripped by the head and guiding such compacted group into an awaiting crate.

Another object of the invention is the provision of improved case-positioning mechanism for holding the case in a carton-receiving position.

Primarily, because of the difficulty in introducing the carton flaps or flanges between each pair of cooperating carton-gripping jaws by means of which the cartons are gripped when only one jaw moves, as was the design of the head disclosed in the original application, another object of the invention is the provision of a carton-gripping head in which both jaws will move to a carton-receiving position and will thereafter close upon the upstanding flap or flange of a carton disposed between the jaws.

Certain features of the machine disclosed in this application are readily adaptable, as will be apparent to those skilled in the art, to machines for handling containers other than gripping an upstanding flap or flange at the top of the containers.

In the accompanying drawings, wherein illustrative embodiments of the invention are disclosed:

Fig. 1 is a top plan view of the apparatus constructed in accordance with the invention;

Fig. 2 is a sectional view, taken substantially on the line 2—2 of Fig. 1, looking in the direction of the arrow;

Fig. 3 is an end view of the apparatus, with parts in section, looking at the same from the left of Fig. 1;

Fig. 4 is a sectional view, taken substantially on the line 4—4 of Fig. 3, looking in the direction of the arrow;

Fig. 5 is a sectional view, taken substantially on the line 5—5 of Fig. 3, looking in the direction of the arrow;

Fig. 6 shows the box-aligning device in its engaged position against a box or crate in position to receive its loading of cartons;

Fig. 7 is a similar view showing the box or crate being raised to a position where it is about to engage the aligning device;

Fig. 8 is a view at right angles to Fig. 6, with parts in section;

Fig. 9 is a top plan view of the plunger, with its upper portion or cover removed to disclose construction;

Fig. 10 is a sectional view on the line 10—10 of Fig. 9 looking in the direction of the arrows;

Fig. 11 is a top fragmentary view of a modified form of the machine looking down upon the carton-marshaling station at the entry side of the carton-gripping station;

Fig. 12 is a cross sectional view taken on the line 12—12 of Fig. 11 and showing the carton-gripping head during the descent thereof to deposit a caseload of cartons in an awaiting case;

Fig. 13 is a cross sectional view taken substantially on the line 13—13 of Fig. 12 and illustrating a modified and improved form of the case-positioning mechanism;

Fig. 14 is a cross sectional view taken on the line 14—14 of Fig. 13;

Fig. 15 is a cross sectional view taken on the line 15—15 of Fig. 13;

Fig. 23 is a schematic wiring diagram of the electrical circuits of the improved form of the machine shown in Figs. 11—12.

ORIGINAL DISCLOSURE

The type of caron or container 1 handled by the apparatus to be described, is the so-called square type made of paper or cardboard, usually wax-coated, and generally used for containing milk, fruit juices and other liquids. Such type of carbon or container is provided at the top with an upstanding turned-over flap that results in a flange 2 (Fig. 2) which, in the present apparatus, is used for engagement of the container and the lowering of it into position in the box or crate in which a number of the cartons or containers are simultaneously placed by the present apparatus.

Described briefly, the apparatus moves a line of the containers or cartons along a traveling belt to a position where successive rows of these cartons are pushed off onto a slidable supporting plate, and in position below a reciprocating plunger. When a predetermined number of the rows of cartons are positioned below the plunger, jaws on the plunger close on the flanges of the cartons and grip the same; the slidable plate is withdrawn from below the cartons so that they are then wholly supported by the plunger. In the meantime, a crate or box has been moved

into raised position directly below the plunger which then descends, lowers the cartons held by it into the crate and releases the same. The plunger then rises and the carton-filled crate is lowered and removed.

Referring to the drawings, 3 indicates the conveyor belt by which a row of the cartons is carried, the cartons having been previously filled with liquid, and are carried in an upright position along on the conveyor belt toward the left as viewed in Fig. 1. The conveyor belt 3 extends about suitable rollers, one of which is carried on the driven shaft 4, which carries the sprocket 5 over which a drive chain 6 extends from a suitable electric motor drive. As the conveyor belt 3 carries the cartons toward the left, as viewed in Fig. 1, the cartons are halted by a fixed stop plate 7 extending upwardly from a horizontal supporting plate or table 8. Mounted for reciprocating slideable movement on the table 8 is a plunger herein referred to as a pusher plate 9, having guide rods 11 slideably guided through the sleeves 10 mounted on the table 8. The pusher plate 9 is provided with a piston rod 12 connected to a piston operative in hydraulic cylinder 13 mounted on the table 8. The operation of the hydraulic piston in cylinder 13 in one direction is controlled by an electric switch 14 having an actuating plate 15 positioned in an opening 14a (Fig. 3) in the stop plate or abutment 7 and in the path of the cartons carried along by the conveyor belt 3. When the first carton in the row carried on the conveyor is halted by the abutment plate 7 and comes into contact with the switch plate 15, it will operate the switch 14 to cause an electric circuit to become operative to cause a solenoid valve to create a flow of hydraulic fluid through port 17 to move the piston in the hydraulic cylinder 13 and hence move the piston rod 12 and pusher plate 9 attached thereto, toward the upper part of Fig. 1. Thus, a predetermined number of cartons then in a row on the conveyor in front of the pusher plate 9 will be urged by the pusher plate to a position below the plunger as shown in Fig. 2, the plunger being therein generally indicated at 25. In the embodiment shown, five cartons are simultaneously urged under the plunger by each stroke of the pusher plate 9. Since the length of the stroke of the pusher plate 9 is constant, each row of cartons as it is urged by the pusher plate, will contact and move the row which preceded it under the plunger, until the required number of rows of cartons necessary to fill a box or crate will be positioned under the plunger 25.

As will be seen in Fig. 1, the pusher plate 9 is formed with a right-angled extension 21 which becomes disposed across the conveyor belt 3, while the pusher plate is in its advanced position, the extension 21 forming a barrier to halt movement of the line of cartons then on the belt until the pusher plate 9 returns to its retracted position, or that shown in Fig. 1. After each forward or carton-moving stroke of the pusher plate, it is retracted and such retracting movement is effected by the hydraulic piston in cylinder 13, the piston being urged back by the hydraulic fluid entering through port 20, the flow thereof being controlled by a solenoid valve of conventional form operated by an electric circuit under the control of microswitch 19. Said switch 19 is provided with a roller 23 operated by the cam 22 on the plate 21 when plate 9 reaches its advanced position.

As the cartons are moved by the pusher plate 9 to a position under the plunger 25, they move across and become positioned on a slideable supporting surface in the form of a horizontal plate 26. Said plate 26 is slideably reciprocated in guideways 27 provided on the table 8. As will be seen in Fig. 2, the plate 26 has its under surface provided with a clevis 28 pivotally connected at 30, to one end of a link 29 which has its opposite end pivoted at 31 to one end of a piston rod 32. Piston rod 32 is connected to a piston contained in the hydraulic cylinder 33 mounted on a plate 34 forming part of the framework of the apparatus. It will be apparent from the structure

described, that the plate 26 may thus be positioned either directly below the piston 25 to thereby support the cartons that have been moved by pusher plate 9 to a point below the piston, or else may be drawn from below the plunger, and cartons below the plunger, to allow the cartons then gripped and supported by the plunger 25 to be lowered into a box or crate then positioned below the plunger. The reciprocating movements of the piston in hydraulic cylinder 33 are controlled by an electric circuit, of which the two micro-switches shown at 36 and 58 form a part. The switch shown at 36 controls the forward movement of the plate 26 to its carton-supporting position. That is to say, when the plunger 25 reaches its elevated position, as shown in Fig. 2, a block 37 carried on top of the plunger 25 contacts the roller 38 of the switch and operates the switch. The switch 36 is mounted in a stationary position on the upper end of one of the guide posts 39 on which the piston is vertically reciprocable.

The switch shown at 58 is mounted on the head of the plunger 25 and in addition to operating means for retracting the plate 26 to non-supporting position, this switch also controls means for maintaining the pusher plate 9 in its advanced position during descent and rise 25 of the plunger.

When the plate 26 is in its advanced or carton-supporting position, lugs 40, provided on the bottom of the plate, ride up on cams 41 located in the guides 27 (see Fig. 2) and this slightly elevates the plate. When 30 the plate 26 starts its retracting movement toward the right in Fig. 1, the plate lowers slightly and is thus prevented from frictionally scraping across the bottoms of the cartons that are at that time engaged by the flanges 2 by the gripping jaws of the plunger 25 now 35 to be described in detail.

The plunger is more clearly shown in Figs. 2, 9, and 10, wherein it will be seen that it includes a frame 42 containing a plurality of spaced-apart fixed jaws or grippers 43, extending across the frame, and a plurality of 40 cooperating movable or pivotal jaws 44. Thus, a flange 2 at the top of a carton is gripped between one of the movable jaws 44 and one of the fixed jaws 43, as will be apparent from Fig. 2. It will be understood that each of the jaws is of a length to enable a fixed and 45 movable jaw to simultaneously grip all of the cartons in one row. Therefore, as seen in Fig. 2, each pair of cooperating jaws 43 and 44 will grip all of the cartons in each of the five rows positioned below the plunger. Each of the movable jaws 44 is pivoted at 45, and carries an arm 46 pivotally attached to a bar 47. The two bars 47, employed as clearly shown in Figs. 9 and 10, are connected or coupled together by the cross bracket 48, provided with the clevis 49 pivotally connected to one end of a link 50, the opposite end of the 50 link being pivotally connected to a clevis 51 at the end of a piston rod 52 connected to a piston reciprocable in a hydraulic cylinder 53. The cylinder 53 is supported and carried by the plunger head and its operation in closing the movable jaws 44 is controlled by an electric circuit including the switch shown at 54. Said switch 54 is operated by a finger 55 having an end portion 56 normally located in the path of the cartons that are moved to position below the plunger 25. That 55 is to say, when the required number of cartons is positioned below the plunger, the cartons in the first row, or those closest to the finger 55, will contact the finger, as shown in Fig. 10, and cause it to close circuit through the switch 54. Through a suitable solenoid valve, this will cause the piston in cylinder 53 to be moved toward the left as viewed in Fig. 2, and cause the movable jaws 44 to be swung toward the fixed jaws 43, thus causing the carton flanges 2 to be gripped between the several pairs of jaws. As piston rod 52 moves toward the left as above described, a bracket 56 carried by it 60 will contact the roller 57 of the switch 58 causing said

switch to close circuit to a solenoid valve controlling the hydraulic flow to the cylinder 33, whereupon the piston in said cylinder will become operative to move the plate 26 from under the cartons then supported by the plunger, the plate 26 being thus moved to the right as viewed in Fig. 1. The cartons, being now grip-pingly supported by the jaws of the plunger, are in position to be carried downwardly by the plunger and deposited into a box or crate then positioned below the plunger.

The plunger is provided with an upper housing 99 including an arm 91 that is vertically guided on the posts 39, 92, and 93 which are fixed in the frame of the machine. The descent and rise of the plunger 25 is attained by means of a hydraulic cylinder shown at 94, the piston rod 95 thereof being connected to the plunger arm 91. The plunger is caused to descend by operation of the piston in cylinder 94 controlled by a conventional solenoid valve in an electric circuit in which the switch shown at 96 is included. The roller 97 of switch 96 is in position to be engaged by a cam 98 (Fig. 2) on the bottom of plate 26, when the plate reaches its retracted position and is out of the path of descent of the plunger 25. Thus, when switch 96 is operated as above described, the plunger 25, carrying the cartons gripped by the flanges 2, can descend to place the cartons in the crate then positioned below the plunger. When the plunger, carrying its load of cartons as above described, reaches its lowest point of descent, the movable jaws 44 are swung to open position, thus releasing the cartons and allowing them to be received by the crate. The movement of the jaws 44 to open position is carried out by the hydraulic cylinder 53 under control of a switch 35. The switch 35 is located in the path of a projecting bracket 99 carried by the cylinder head and said bracket operates the switch at the proper time to cause opening of the jaw and the resultant release of the cartons.

The crates 65 to be successively positioned below the plunger 25 are moved along supporting rails 60 and 61, between the guard rails 62, by means of the continuously moving chain 63, riding in the channel bar 64. These crates are preferably of wood or metal, or combinations of these materials, but might also be of corrugated cardboard. In Fig. 4 one of the crates, or that shown at 65a, is in carton-receptive position, positioned directly below the plunger 25. As each crate is moved along by the chain 63, it enters between a fixed guide rail shown at 66, and an opposite, resiliently mounted guide rail shown at 67. The latter guide rail is resiliently mounted by means of the springs 68 interposed between the telescoping parts 69 and 70, the parts 69 being carried by the guide rail 67, and the parts 70 being fixedly mounted on the support 71 forming a part of the machine frame 72. When the crate to be filled reaches the station indicated at 65a where it is to receive the cartons upon lowering movement of the plunger 25, the forward end wall of the carton comes into contact with a pivoted finger 73 as shown in Fig. 4, which, on its pivotal movement under pressure of the wall of the crate against it, contacts the roller 74 of the switch 75 thus causing said switch to close an electrical circuit operative upon a conventional solenoid valve, the operation thereof controlling the movements of a piston in a hydraulic cylinder 76. The piston rod 77 connected to the piston in said cylinder 76, is attached to a bar 78 provided at its opposite ends with the stops indicated at 79 and 80. When the piston rod 77 is projected in a direction out of the cylinder 76, the stops 79 and 80 will embrace the crate and tend to straighten or line it up in properly registered position with respect to the plunger 25 located above it. At the same time, the following crates will be halted, not only by the stop 80, but by the pivoted toggle 81, provided at one end with the head 82 which enters between the first crate 65a

and the following one, or that indicated at 65b, thus slightly tilting or angularly positioning the second crate, this action being facilitated by the finger 83 provided on the guide rails 62. The toggle 81 has its second arm 84 provided with a roller 85 operative against the side wall of the crate to also aid in maintaining the crate properly positioned for filling.

When the crate to be filled is positioned below the plunger 25 as above described, it is located above an elevator 100 by which it is raised as indicated in dotted lines in Fig. 3. The elevator 100 is supported by the piston rod 101 connected to a piston in the hydraulic cylinder 102, the elevator being guided in its raising and lowering movement by its bosses 103 slidable on the guide rods 104. The operation of the hydraulic cylinder is controlled by a suitable solenoid of known character controlled by an electric circuit of which the switch 54 forms a part. That is to say, when switch 54 is operated by contact of its finger 56 with the first row of cartons under the plunger, the elevator will be raised by operation of the hydraulic cylinder to the position indicated in dotted lines in Fig. 3 and supported in such raised position while the cartons are deposited into the crate by the descent of the plunger and release of the cartons 25 by it.

When the crate is elevated as above described, its upper edge will contact with a spring-pressed roller 110 and will deflect the roller to allow a foot 111 to come into contact with the top edge of the crate. The foot 111 is formed as part of a plunger 112 which is spring-pressed by the coil spring 113 contained in a housing 114. The housing 114 is pivotally attached at 115 at the end of an arm of a bell crank 116, mounted on the fixed pivot 117. The second arm of the bell crank 116, indicated at 118, is formed with a clevis in which a roller 121 is rotatably mounted at 120.

The above described arrangement and its operation is clearly shown in Figs. 6, 7, and 8. In Fig. 7 the crate is shown in its ascending movement and its upper edge 40 about to contact with the roller 110. As this edge of the crate contacts with the roller 110, the roller is deflected to allow the foot 111 to come into contact with the top edge of the crate as shown in Figs. 6 and 8. This contact tends to swing the bell crank on its pivot 117, 45 bringing the roller 121 against that side wall of the crate that is positioned at right angles to the wall contacted by roller 110. This arrangement is such that the box is lined up while on the elevator, assuring its proper position with respect to the plunger and the cartons carried 50 thereby so that the cartons will be accurately placed in the crate.

When the cartons reach a position close to the bottom of the crate, the jaws 44 are opened and the cartons released to rest on the bottom of the crate. The elevator 55 100 now descends carrying the filled crate, and upon its descent it contacts a switch shown at 122 which is effective in an electric circuit to cause piston rod 77 to be retracted and the stop member 79 thus drawn out of the path of the now lowered and filled crate which may 60 then be carried by chain 63 to a point of unloading.

From the foregoing, the operation of the described apparatus will be understood. The filled cartons are carried along on the conveyor 3 until the first carton in the row on the conveyor reaches the stop 7 where it is halted 65 and where it actuates switch 14. This causes pusher plate 9 to move five of the cartons 1 toward the plunger 25 and under the plunger. The actuation of switch 19 by cam 22 causes retraction of the pusher plate and when another carton in the row on the conveyor reaches the 70 abutment 7 and actuates the switch 14 a second row of five cartons will be pushed by the pusher plate 9 to position under the plunger. The second row, thus urged forwardly by the pusher plate, will slide the row previously advanced further under the plunger. This is repeated until the required number of rows of cartons 75

has been positioned under the plunger. When this occurs, one of the carsons in the row first positioned under the plunger, will contact switch finger 56 as shown in Fig. 10, and this will actuate the switch 54 and cause the movable jaws 44 to cooperate with the fixed jaws 43 in gripping the flanges 2 of the cartons then located under the plunger. Switch 54, being thus actuated, will operate to hold the pusher plate 9 in its advanced position so that its side portion 21 will block the conveyor and cartons on the conveyor will be held against movement. Switch 54 is also operative to raise the elevator 100 so that the crate 65a then under the plunger, will be elevated as previously described. As the piston rod 52 moves in a direction to close the movable jaws 44, the bracket 56 carried by it will actuate switch 58, causing plate 26 to be retracted from below the plunger so that the plunger 25 will then be free to descend into the crate with its load of cartons. As plate 26 moves to its retracted position or out of the path of plunger 25, its cam 98 will contact switch 96 and actuate the same to cause lowering of the plunger. When the plunger reaches its lowered position, bracket 99 will contact switch 35 and actuate the same to cause the movable jaws 44 to be moved to open position, so that the cartons will thereupon be released by the jaws and can come to rest within the crate. The filled crate is then lowered by the elevator 100 and as this is done, the elevator, contacting with the switch 122, will cause the stop 79 to be drawn out of the path of the filled crate so that the filled crate can be carried away by the chain.

When the plunger releases the cartons into the crate, the contact between the cartons and the finger 56 is lost, and the switch 54 is then actuated in a manner to cause operation of the piston in cylinder 94 to elevate the plunger to its raised position and retain it in such position until it is again charged with a load of cartons. When the plunger reaches its raised position as above described, the block 37 is brought into contact with the roller 38 constituting part of the switch 36 which closes circuit in a manner to operate the piston in cylinder 33 and cause the plate 26 to be advanced, or brought to carton-supporting position beneath the plunger 25. When the plate 26 reaches this advanced position, a cam 135 on its under side actuates a switch 136 which closes an electrical circuit to cause switch 19 to then become effective and close circuit to cause piston in cylinder 13 to retract the pusher plate 9 and bring the extension 21 out of the path of the conveyor and the cartons carried thereon. This enables the cartons on the conveyor to be again moved to the left, as viewed in Fig. 1, until the first carton in the line on the conveyor 3 reaches the abutment plate 7 and contacts the switch plate 15 to begin the cycle of operations just described.

Additional disclosure

The machine shown in Fig. 11 at seq. is an improvement upon the machine heretofore described in a number of respects, one of which is that it is capable of marshaling a full caseload of cartons while a previously marshaled caseload is being deposited in an awaiting case. This increases the machine's efficiency because, as soon as the plunger or carrier has returned to its starting or carton-receiving position, the newly marshaled caseload can be pushed as a complete unit into position beneath the plunger and thereafter deposited in an awaiting case. There is no need for any delay as occasioned by the original embodiment heretofore described where one row at a time is pushed off the infeed conveyor 3 and onto the retractable table 26, with the case-filling stroke of the plunger being withheld until the table is full. This particular advantage is attained by providing a carton-marshaling station or area A, see Fig. 11, adjacent the plunger or carrier capable of holding a full caseload of cartons with a pusher 9a operable to fill the area with a caseload while simultaneously a previous caseload

is being deposited by the plunger in an awaiting case, with the pusher operable to move the marshaled caseload as a unit beneath the plunger as soon as the plunger has returned to its carton-receiving position. For convenience, the retractable floor 26 and the area thereabove is referred to hereinafter as the transfer station. The carrier or plunger grips the containers in the transfer station for transfer to an awaiting case.

The improved machine is of basically the same construction as that heretofore described except as specified hereinafter. The infeed conveyor, instead of comprising one belt, includes two belts 3a and 3b, see Fig. 11. While one belt might be employed, a two-belt conveyor allows the machine to operate faster and reduces the number of strokes of the pusher in order to assemble a caseload of cartons. It will be apparent to those skilled in the art following this description that more than two belts might be provided to increase to an even greater extent the machine's efficiency. A pair of normally closed electric backing switches LS-11 (only one of which is shown in Fig. 23 to represent both), one adjacent each belt and each provided with a carton-actuated arm 142, serves to sense a backlog of cartons on the belts for purposes hereinafter described. The extension 9b of the pusher 9a which extends across the belts 3a and 3b serves as a gate preventing cartons on belts 3a and 3b from entering the marshaling area while the pusher is in the extended position.

The infeed belts 3a and 3b deliver the cartons to the carton-marshaling station generally indicated as A with the belts comprising substantially one-half the floor space of the station and the table 8a between the inboard belt 3b and the retractable table 26 comprising the balance of the floor space. The general outline of such marshaling area is defined by the wall 144, the pusher 9a when in the retracted position shown in Fig. 11, and the dotted lines 146 and 148. Such area is substantially the same as that occupied by a grouped caseload of cartons. Cartons on the conveyor belts are indicated at C₁.

As conveyor belts 3a and 3b deliver cartons C₁ to the marshaling station, the leading cartons of the two rows entering the area actuate a pair of electric switches LS-3 and LS-13 mounted on table 8a as switches 14 heretofore mentioned and electrically connected together in series to a time delay relay TR-2 (see Fig. 23). The relay waits a short interval to ensure that two full rows of cartons are in front of pusher 9a and then energizes, through closure of TR-2, a solenoid-operated valve, 3-B, controlling admission to a fluid pressure cylinder similar to cylinder 13 shown in Fig. 1 causing piston rod 12a to be extended, moving pusher 9a across the conveyor belts and in turn sweeping the cartons off the belts and onto that portion of table 8a between the inboard belt 3b and the retractable table 26. When the cartons reach the positions indicated as C₂, LS-7 is actuated by the cartons serving to de-energize solenoid 3-B and close the valve admitting fluid pressure to the pusher cylinder and the pusher stops moving. It will be noted that the cartons swept from the two belts by the pusher 9a is equivalent to two full case rows of cartons.

Switches LS-11 are termed backlog switches because they only allow the pusher 9a to retract from its extended position after a determined backlog of cartons builds up on belts 3a and 3b outside of the marshaling area upstream of the pusher extension 9b. The switches LS-11 are spaced upstream of conveyor belts 3a and 3b by a distance such that a full case row of cartons may be disposed on each belt between the pusher extension 9b and the switches. In practice it is preferable to so position switches LS-11 that not only will a full case row of cartons be disposed upstream of the pusher extension 9b on each belt between it and the switches, but also a few additional cartons such as 2 or 3. In other words, with the pusher in the extended position

and with its extension 9b blocking the entry of cartons on belts 3a and 3b from entering the marshaling area, the pusher will not be allowed to retract until a case row of cartons plus two builds up on each belt. With this backlog created, the pusher will then retract.

Normally closed switches LS-11 are electrically connected, as shown in Fig. 23, with a time delay relay TR-3, whereby the switches must be held open by cartons for a determined length of time before they are operative to cause the retraction of the pusher, it being understood that a carton passing by the switches and actuating the switch arms will serve to momentarily open the switches. When the time interval of relay TR-3 expires, it serves to energize solenoid valve 3-A connected to one end of the pusher cylinder to pressurize the cylinder and cause pusher 9a to retract to the position shown in Fig. 11.

Thereafter, and independently of whether the caseload beneath the plunger is deposited in an awaiting case, marshaling area A is again filled with cartons as before described. Once area A is full of cartons, pusher 9a will not be extended to push the caseload beneath the plunger unless the retractible table is ready to receive cartons.

It is now apparent that the improved embodiment is capable of marshaling one caseload of cartons while another caseload is being deposited in an awaiting case. As a result, both the efficiency and the capacity of the machine are increased.

As mentioned, the pusher will remain in this position until the backlog switches LS-11 indicate that there is a backlog of cartons between portion 9b of the pusher and switches LS-11 consisting of two full case rows of cartons plus two, at which time the pusher will retract to its starting position. With the pusher retracted, cartons on belts 3a and 3b over again enter the marshaling area and the leading cartons contact switches LS-3 and LS-13. Now the marshaling area is completely filled and the caseload is ready to be pushed onto the table 26, provided the table 26a is in a carton-receiving position. If table 26 is in a carton-receiving position, switch LS-6 will be held closed by the table. LS-6 corresponds to switch 136 shown in Fig. 1. With LS-6 closed, and switches LS-3 and LS-13 also closed, the plunger is extended to push the entire caseload onto the retractible table and beneath the plunger. On this stroke the plunger's movement is not interrupted by switch LS-7 as occurred on the first stroke because LS-7, though open, is bypassed by switch LS-6 as shown in Fig. 23. Therefore the plunger continues to move and sweeps the entire caseload onto the retractible table. As the cartons reach their fully loaded positions on the table, pusher 9a by an offset switch tripper 145 mounted on the pusher and extending through a slot (not shown) in wall 144, closes switch LS-14 mounted on the machine frame. As shown in Fig. 23, closure of LS-14 energizes time delay relay TR-4, which in turn, through the switches TR-4, serves to cut off fluid pressure to the pusher cylinder and energize solenoid 1-B to cause hydraulic cylinder 53 to actuate the carton-gripping jaws to grip the cartons. Upon gripping the cartons LS-9 is tripped (corresponding to switch 58 of Fig. 1) causing retraction of the table. The plunger will now deposit the cartons if a case is properly disposed in a carton-receiving position.

It will be noted that the stroke of piston rod 12a in this embodiment is of two different lengths. One length, the shorter one, is sufficient only to push two rows of cartons off belts 3a and 3b to the positions C₂, while the longer stroke is sufficient to push the entire caseload of cartons onto the retractible table 126a.

In order to ensure each caseload of cartons properly enters a case positioned to receive it, the cartons are compacted together as a grouped caseload while they are gripped at their tops by the carrier head of the plunger. Because the cartons are formed of paper or the like and

are liquid filled, and because the paper is relatively thin, the cartons are subject to bulging. While the tops of the cartons are compacted together by virtue of their suspension from the carrier, they are free to spread apart at the bottom because of the flexibility of the flaps 2 by which they are gripped. This spreading apart of the cartons at the bottom frequently results in the bottoms catching on the upper edges of a case waiting to receive them; or if the cases are made sufficiently large to receive the cartons there is considerable sloppiness of the load in the case once the cartons have been released. Unless the sides of the case serve to support the sides of the cartons once they have been deposited in the case, subsequent transport of the case and the accompanying jarring thereof will tend to cause the cartons to bulge even more and leaky cartons will result. Preferably the cases should be so sized relative to the caseload of cartons that the cartons as a group, upon release of their suspension from the plunger head, will bulge only slightly and contact the walls of the case to be supported thereby, with the caseload fairly tightly fitting within the case.

To prevent bulging of the cartons suspended from the carrier from enlarging the grouped caseload sufficiently so that it catches on the upper edges of an awaiting case, to prevent a bulging caseload from scraping against the sides of a case and giving rise to possible puncturing of cartons at the sides of the caseload, and in order to allow a caseload of cartons to be tightly packed within an awaiting case, the caseload is received by compacting means which compacts the caseload of cartons together, prevents bulging thereof, and serves to guide the caseload into an awaiting case. Such compacting means includes a three-walled boxlike enclosure having side wall portions 160, 162, and 164, and a pivoted wall portion of guide 166. Wall portions 160, 162, and 164 are in the form of skirts or thin metal plates depending from the carrier head or plunger 25a as shown in Figs. 12, 19, and 22. These wall portions or skirts may comprise a single sheet of metal bent at 166 and 168 and secured as by screws or the like 170 to the head. At the carton entry side of the compacter, skirts 160 and 164 are tapered at the edges as at 172 in order that the cartons are quided into the space between the walls 160 and 164. In order to facilitate the guiding of the cartons into the compacter, as well as prevent the overtravel of cartons being pushed to the C₂ positions, by the first or shorter stroke of the plunger 9a, a spring-loaded guide member 176 mounted on plate 8a and shown in Fig. 11 extends between conveyor side wall 178 and a point closely adjacent the edge 172 of skirt 164.

Compacter skirts 160, 162, and 164 extend downwardly from the carton-gripping head 25a to a point just above the retractible floor 26 when the carrier head is in the carton-receiving position. The skirts, as shown in Figs. 12, extend down alongside the cartons for approximately three-quarters of their vertical dimension. This will allow the same skirts to be used for the deposit of smaller cartons, i.e., those having a lesser vertical dimension because they will allow the head to be disposed lower over the retractible table as well as permit the head to enter a case to a greater depth.

As the carrier head descends following retraction of floor 26, the lower edge of that row of cartons adjacent pivoted guide 166 strikes the guide and pivots it from the dotted outline to the solid outline position shown in Fig. 12. It will be noted that guide 166 is received within the upper edge of an awaiting case so that the lower edges of the cartons adjacent the guide are guided into the case as shown in Fig. 12. The guide is spring-loaded and normally held in the dotted outline position. The spring forth the guide is indicated at 180 and is connected thereto in any suitable fashion. The guide comprises an elongate strip of metal extending through-out substantially the entire length of a caseload of cartons

and is mounted for pivotal movement upon a rod supported at opposite ends in brackets 182 and 184 mounted on the frame of the machine. Pivoted guide 166 together with skirts 160, 162, and 164 guide the caseload of cartons into the awaiting crate.

Because it is desirable to keep the wall thickness of skirts 160, 162, and 164 to a minimum, skirts 160 and 164 are subject to outward deflection at their lower edges because of the outward pressure of the cartons contained therebetween. To prevent this outward deflection I have provided bearing blocks or the like 186, 188, and 190, shown in Figs. 11 and 19, mounted in any suitable fashion, as by angle brackets 192 and 194, on the frame of the machine and against which the skirts 160 and 164 bear during downward movement into an awaiting crate; Bearing blocks 186, 188, and 190 prevent the lower edges of skirts 160 and 164 from deflecting outwardly under the pressure of the compacted caseload of cartons and prevent the lower edges of such skirts from catching on the upper edges of an awaiting case. Such bearing blocks may be provided with a nylon bearing face in order to reduce wear on the skirts. The two blocks 188 and 190 are provided rather than one continuous block as with block 186, in order to allow the piston rod 32 of ram 33 operating the retractible table 26 to extend between the blocks.

As shown in Fig. 19 the blocks 186, 188, and 190 will serve to prevent outward deflection of the lower edges of the skirts prior to their entry within the top of an awaiting case. Once the lower edges of the skirts have entered the top of the case, outward deflection of the lower edges of the skirts will encounter the inner wall surfaces of the case and the case itself will guide the skirts. When the cartons suspended from the carrier head near the bottom of the case, switch means described in connection with the original disclosure serve to cause the carrier to release the cartons with the carrier thereafter returning upwardly to its original position. As the carrier ascends the skirts are withdrawn from between the caseload of cartons and the inner wall surfaces of the case, and the caseload of cartons is thereupon free to expand slightly to abut the inner wall surfaces of the case. It has been found that with the compacting means herein described, a caseload of cartons may be deposited in an awaiting case more tightly than could such cartons be placed in the case by hand, a few cartons at a time.

It is apparent that with the use of the compacting skirts and their close interfitting within the open upper end of an awaiting case, it is necessary to position the case very accurately and hold it in proper alignment with the downward movement of the carrier head so that the compacting skirts and the caseload of cartons will be received properly within the awaiting case. As pointed out in the original disclosure, a case elevator 100 is provided. This elevator is shown also in Figs. 13, 16, and 19. It is operable to elevate a case off the case conveyor 63 and hold the case during the deposit of cartons therewithin, and thereafter lower the case back to the case conveyor, for transport out of the machine. The details of construction and operation of the case elevator need not be repeated at this point except to mention that the elevator includes a pair of flat plates 196 and 198 upon which a case is supported and upon which the case may be slidably shifted. Considering Figs. 13-15 and 19, it will be noted that cases enter the machine on the continuously operative conveyor 63 in the direction of arrow B with their movement being initially arrested, assuming a case is disposed upon the case elevator, by a case stop 200. Case stop 200 is mounted upon a rod 202 supported at opposite ends in brackets 204 and 206 secured in any suitable fashion to the frame of the machine. Stop 200 is rotatable about rod 202 and is actuated by a fluid pressure cylinder-piston combination 208 the lower end of which is pivotally connected as at 210 to the frame of the machine with the upper end of

the combination pivotally connected as at 212 to the stop. Upon extension of piston rod 214 the stop is moved to the solid outline position shown in Fig. 14 while upon retraction of the piston rod the stop is moved to the dotted outline position. The stop is generally L-shaped as shown and is provided with a case-engaging ear 216 adapted to extend downwardly in front of either the leading upper edge of a case indicated at CS and prevent movement of the case on the conveyor or downwardly within a case to abut in the inner wall surface of the rear wall of the case. The ear 216 will extend down within the top of the case to engage the inner surface of the rear wall of the case if there is a solid line of cases on conveyor 63 in end-to-end abutting relation.

In the event that no case is disposed on the case elevator, the stop 200 is shifted to the dotted outline position to allow a case to pass over the elevator. As a case CS₁ moves over the elevator, it intersects the beam of an electric eye unit PE, see Fig. 23, which includes an exciter lamp L positioned within the machine at a location shown at 218 in dotted outline in Fig. 13. The electric eye unit is of conventional construction and need not be described in detail. When the light beam of the electric eye is interrupted by the case CS₁, the case stop cylinder 208 is pressurized by energization of solenoid 4-B by closure of switch PE-2 to move the stop 200 from the dotted to the solid outline position of Fig. 14, with the ear 216 extending down through the top of the succeeding case CS₂. Solenoid 4-B is operatively connected to a fluid pressure valve (not shown) controlling admission of fluid pressure to the lower end of cylinder 208, whereby upon energization of solenoid 4-B, the cylinder is pressurized at the bottom to swing the stop as aforesaid.

Both cases CS₁ and CS₂ continue to travel until the rear wall of case CS₂ comes up against ear 216 whereupon further movement of such case is arrested. At about the time that movement of case CS₂ is arrested by stop 200, elevator cylinder 102 raises the elevator to lift case CS₁ off the conveyor. Cylinders 102 and 208 are both controlled by the same valve which is operated by solenoid 4-B but there is a flow-control valve between such valve and cylinder 102 which delays the operation of cylinder 102. It is during this delay that the case stop 200 intercepts case CS₂, arrests its movement, and allows case CS₁ to continue moving so that a separation of approximately 1/2" occurs between cases CS₁ and CS₂ at the time CS₁ is elevated.

As CS₁ is elevated it is moved upwardly in front of a case puller 220, which, together with a case presser 245 and stops 240 and 232, positions and holds case CS₁ in the proper carton-receiving position. The case puller 220 is mounted for slidable movement on rod 202. The case puller includes a dog 222 connected by a plate 224 to the piston rod 226 of cylinder-piston combination 228 mounted on the frame of the machine. A coil spring or the like 230 encircles the piston rod 226 to yieldingly urge the dog 222 along rod 202 against the reaction of the case. When the case has been elevated and is positioned in front of the case puller, cylinder 228 is pressurized to move dog 222 against the case and slide the case along the elevator to a position abutting a case-positioning block 232 secured to the rod 202 as shown in Fig. 18.

A case presser 245, shown in Fig. 16, and including a presser arm 238, is adapted to shift the case CS₁ laterally on the elevator and against a stop 240. The presser is suspended from the rod 202 and includes a bell crank arm 246 pivotally mounted on the rod 202 with the arm 238 connected to the bell crank as shown in Fig. 16 and with the opposite end of the crank pivotally connected to the piston rod 254 received in cylinder 250, the latter being pivotally connected as at 252 to the frame of the machine. It is apparent that upon retraction of piston rod 254 to cylinder 250, the presser arm 238 will bear against case CS₁ on the elevator and urge

the same against stop 240. Cylinder 250 is connected to the same fluid pressure line supplying fluid pressure to the puller cylinder 228 such that upon pressurization of cylinder 228 to pull case CS₁ against the block 232, the presser cylinder 252 will also be pressurized to shift the case laterally.

Pivotedly mounted on the stop 232, as shown in Fig. 17, is a switch actuating arm 234, adapted to close switch LS-2 mounted on the frame of the machine when case CS₁ abuts the stop 232 pivoting the arm from the dotted to the solid outline position. Closure of switch LS-2, as shown in Fig. 23, and assuming switch LS-10 (corresponding to switch 96 in Fig. 1) is closed by floor 26 being in the retracted position, the carrier or plunger will be allowed to descend to deposit its caseload of cartons in case CS₁. Unless case CS₁ has been shifted by the puller against the stop 232, switch LS-2 will not be closed and therefore the carrier will not descend to deposit its caseload. Because the presser cylinder 250 is connected in the same fluid pressure circuit as puller cylinder 228, there is assurance that the case will be moved laterally against stop 240 as well as against stop 232 so that the case will be properly positioned to receive the caseload of cartons from the carrier.

The caseload of cartons is released by the carrier closing switch LS-4 (corresponding to switch 35 shown in Fig. 1) which, as shown in Fig. 23, causes energization of relay TR 1 in turn opening its enslaved switch TR-1 to de-energize relay G and to de-energize solenoid 1-B which controls a valve admitting fluid pressure to the carton-gripping cylinder 53 (shown in Fig. 1). De-energization of relay G causes closing of its normally closed enslaved switch G resulting in energization of solenoid 1-A. Solenoid 1-A controls operation of a fluid pressure valve admitting fluid pressure to cylinder 53 causing such cylinder to shift the carton-gripping jaws in the open position releasing the cartons in the case. De-energization of relay G also serves to open its switches G one of which, as shown in Fig. 23, serves to de-energize relay C which in turn allows a normally closed enslaved relay switch C to close thereby energizing solenoid 5-A. Solenoid 5-A controls admission of fluid pressure to the cylinder 94 to cause the piston rod 95 thereof (see Fig. 3) to be extended to raise the head away from case CS₁. As the carrier reaches its elevated position, it closes switch LS-5 (corresponding to switch 36 shown in Fig. 1) which, as shown in Fig. 23, causes de-energization of relay TR-1 and the energization of solenoid 2-A. Solenoid 2-A controls operation of the table cylinder 33 causing the cylinder to be pressurized to move table 26 to its carton-supporting position, it serves to close LS-6 (corresponding to switch 136 shown in Fig. 1) and permitting the pusher to push another caseload of cartons onto the table beneath the carrier in preparation for a repeat cycle of the machine.

When TR1 is de-energized by the opening of LS-5, one of its functions is to close its enslaved switch TR-1 shown at the lower left-hand corner of Fig. 23 which causes energization of solenoid 4-A. Solenoid 4-A controls operation of the fluid pressure valve admitting fluid pressure to the case-elevating cylinder 102 causing the cylinder to lower the case elevator 100 to deposit case CS₁ back on the case conveyor which carries the case out of the machine. Solenoid 4-A also serves to reversely pressurize the puller cylinder 228 and the presser cylinder 250 to return the puller and the pressure to their starting positions. It also reversely pressurizes case stop cylinder 208 to raise the case stop ear 216 out of case CS₂ to allow such case to enter the case-positioning station over the elevator. The machine is now ready to recycle.

The improved carton-gripping head is shown in Figs.

20-22, inclusive, and comprises a boxlike frame having end frame members 256 and side frame members 258 secured together at their meeting ends. The boxlike frame is closed at the top as by a plate 260. Disposed within the frame and depending therefrom are a plurality of pairs of coacting cooperating carton-gripping jaws, each pair of jaws comprising jaw members 260 and 262. Each jaw is supported for movement toward and away from the opposite cooperating jaw to gripingly engage the flap 2 of a carton disposed between the jaws. The jaws are retractable from the solid outline position shown in Fig. 20 to the dotted outline position and in such latter position receive the flap 2 of a carton as the carton moves over retractable table 26 along the length of the jaws. When the jaws close together, the flap is gripped therebetween. Each pair of jaws extends completely across the boxlike frame between the inner surfaces of the side walls 258. Each jaw is pivotally supported upon a pair of pivot pins 264 as shown in Fig. 22 received within opposite ends of the opposite jaw and within the side frame members 258. Each jaw of each pair is connected for simultaneous operation with a similar jaw of each other pair. Upstanding from each of the jaws 260 are a pair of rigid earlike portions 266 and 268. Upstanding from each jaw 262 of each pair are a pair of rigid portions 270 and 272. Pivotedly connected as by pivot pins 274 to each of the ears 272 of each of the jaws 262 is an actuating bar 276. To each of the ears 268 of each of the jaws 260 of each pair is pivotally connected by pivot pins 278 an actuating bar 280. In similar fashion bars 282 and 284 are connected to the ears 266 and 270 of each of the jaws of each pair. The pivot pins are secured against rotation within the ears 266, 268, 270, and 272 as by set screws or the like 286 and are pivotally received within the actuating bars.

Extending lengthwise of the boxlike frame of the carton-gripping head and disposed between the actuating bars 276, 280 and 282, and 284 are a pair of crank-supporting members 288 and 290 each secured at opposite ends as by screws or the like 292 to the end frames 256 of the head. Extending transversely of the head and securing at opposite side frames 258 thereof as by screws or the like 294 is a rigidifying member 296 to which the crank-supporting members 288 and 290 are connected as at 298. Pivotedly mounted on each of the members 288 and 290 are a pair of cranks or levers 300 and 302. These cranks or levers are secured to the members 288 and 290 by upstanding pins 304 upon the upper ends of which may be threaded retaining nuts 306 as shown in Fig. 20.

To open and close the jaws a fluid pressure cylinder similar to cylinder 53 of Fig. 1 is mounted on plate 260 and indicated at 53a. The piston rod 52a of cylinder 53a is pivotally connected as at 308 to an actuating link 310 in turn pivotally supported between a pair of blocks, one of which is indicated at 312 in Fig. 20. The blocks are secured to the underside of plate 260 as by screws or the like 314 and the link 310 is pivoted between the blocks on a pin 316. The lower end of link 310 is bifurcated with the bifurcations 318 and 320 received over a pin 322 secured at opposite ends within the actuating bars 280 and 282. It is now apparent that upon pressurization of cylinder 53a to move piston rod 52a in either an extended or retracted direction, link 310 will be pivoted in turn moving actuating bars 280 and 282 and through the levers 300 and 302 the bars 276 and 284. This motion will serve to open and close the jaws 260 and 262 of each pair depending upon the direction in which piston rod 52a is moved.

It will be noted in Fig. 20 that when jaws 260 and 262 are opened to the position shown in dotted outline, cartons will be free to slide across the retractable table 26 with the flaps 2 free to enter the space between the open jaws without danger of the flaps catching on one or the other of the jaws of each pair. With the embodied

ment of the plunger head shown in the original disclosure only one of the jaws was capable of movement, which gave rise to the possibility that the stationary jaw would catch the flaps 2 as the cartons moved across the retractible table with the flaps entering the space between the jaws. The embodiment just described and shown in Figs. 20 and 21 obviates this possibility.

What I claim is:

1. In a machine for depositing articles in cases: means for holding a case in an article-receiving position, an article-marshaling station, an article-transfer station in article-receiving relation adjacent the marshaling station, means for transferring articles from the transfer station downwardly through such station into a case held in an article-receiving position, a retractible floor in the transfer station upon which articles in the station rest prior to transfer by said transfer means, an article conveyor for delivering a line of articles to the marshaling area, pusher mechanism independent of said retractible floor and operable at right angles to the line of articles to marshall the line into successive rows and group the rows into a caseload of articles in the marshaling station in front of the pusher, means coupled with the pusher mechanism and responsive to an empty condition of the transfer station with the retractible floor in an article-supporting position to cause the mechanism to push as a unit a marshaled caseload of articles into the transfer station and upon the retractible floor, and said pusher mechanism operable independent of the presence or absence of articles in the transfer station to marshal another caseload of articles in the marshaling station for pushing to the transfer station when the latter is again empty.

2. In a machine for depositing articles in cases: a case-supporting station, an article transfer station disposed directly above the case-supporting station and having a retractible article-supporting floor for supporting articles moved into the transfer station, a carrier operable to grip at the top articles supported on said floor and transfer the articles downwardly through the transfer station to a case in the case-supporting station, means coupled with the carrier and with said floor to cause retraction of the floor following gripping of the containers, an article-marshaling station for holding a caseload of articles, said transfer station disposed in article-receiving relation adjacent the marshaling station, conveyor means for delivering articles to the marshaling station, marshaling means independent of said retractible article-supporting floor for marshaling articles delivered to the marshaling station into a caseload in the marshaling station and transferring each caseload as a group unit to the transfer station for support by the retractible floor prior to gripping by the carrier.

3. In a machine for depositing in cases filled semi-rigid containers susceptible to lateral bulging and having means at their tops whereby each can be gripped for suspended transfer: a transfer station having means for supporting articles of the aforesaid character in a standing position in the station, a carrier above the station having cooperating article-gripping members for gripping at the tops a caseload of the containers in the station, skirt-like means depending from the carrier and substantially enclosing and compacting together a caseload of containers in the transfer station beneath the carrier, a case-positioning station, said carrier shiftable vertically toward a case in the case-positioning station with said skirt-like means entering the case between the sides thereof and the caseload of containers suspended from the carrier to guide the containers in shoehorn fashion downwardly in the case, means coupled with the gripping means and with the carrier to cause the gripping means to release the articles in the case and cause the carrier to ascend out of the case.

4. In a machine for depositing in cases filled semi-rigid containers susceptible to lateral bulging and having means at their tops whereby each can be gripped for

suspended transfer: a transfer station having means for supporting articles of the aforesaid character in a standing position in the station, a carrier above the station having four sides and cooperating article-gripping members for gripping at the tops a caseload of the containers in the station, compacting means secured to three sides of the carrier and depending from the carrier at three sides of a caseload of containers suspended from the carrier and extending initially downwardly in overlying relation with the sides of the caseload throughout the major portion of the vertical height of the caseload and compacting the caseload together and shiftable with the carrier, means operative adjacent the fourth and open side of the carrier to urge a caseload of containers laterally beneath the carrier and into the enclosure formed by said compacting means at three sides of the carrier, a case-positioning station, said carrier shiftable vertically toward a case in the case-positioning station, with said compacting means depending from the carrier entering the case between the sides thereof and the caseload of containers suspended from the carrier to guide the containers in shoehorn fashion downwardly in the case, and means coupled with the gripping means and with the carrier and operable to cause release of the caseload in the case and retraction of the carrier upwardly out of the case.

5. In a machine for depositing liquid-filled cartons in cases: a case-supporting station, a carton transfer station, a carrier operable between the stations to transfer cartons from the transfer station to a case in the case-supporting station, said carrier including means for gripping each carton at its top for suspended transfer and introduction into an awaiting case, compacting means secured to and depending from the carrier and open at one side and enclosing a caseload of cartons gripped by the gripping means at the remaining three sides and compacting the caseload together, and means operable adjacent the transfer station to move cartons into the station through the open side of the compacting means, and said compacting means shiftable with the carrier and insertable in an awaiting case in the case-supporting station between the sides of the case and the case-load of cartons as the carrier moves toward the case to guide the caseload thereinto.

45. 6. In a machine for depositing liquid-filled cartons in cases: a case-supporting station, a carton transfer station, a carrier operable between the stations and vertically above the case-supporting station to transfer cartons from the transfer station to a case in the case-supporting station, said carrier including means for gripping each carton at its top for suspended transfer and introduction into an awaiting case in the case-supporting station, compacting means secured to and depending from the carrier and open at one side and extending downwardly alongside a caseload of containers throughout substantially the vertical height of the caseload and enclosing the caseload of cartons gripped by the gripping means at the remaining three sides and compacting the caseload together, means pivotally supported adjacent the top of the case-supporting station and at that side thereof adjacent the open side of the compacting means and adapted to be pivoted down into a case supported in the case-supporting station during descent of a case-load of cartons suspended from the carrier and cooperable with the compacting means to guide the caseload into the carton, and means operable adjacent the transfer station to move cartons into the station through the open side of the compacting means.

7. In a machine for depositing articles in cases: an article-accumulating station, a case-supporting station, a carrier operable between the stations to transfer articles from the transfer station to a case in the case-supporting station, said case-supporting station including a case conveyor for delivering cases to and removing cases from such station, a case elevator in the case-supporting station and provided with a case-supporting surface, means re-

sponsive to the entry of a case in the case-supporting station to cause said elevator to ascend lifting the case from the conveyor, means in the case-supporting station for engaging a case on the elevator and shifting the same along the elevator, first positioning means in the case-supporting station for locating a case and against which a case abuts upon shifting by said engaging means, other engaging means in the case-supporting station for shifting a case laterally on the elevator, second case-locating means against which a case is abutted upon shifting by the last-mentioned case-engaging means, and means coupled with the carrier and responsive to the positioning of a case against said case-locating means to allow said carrier to descend to deposit articles in a case.

8. In an apparatus for depositing paper cartons into a crate, which cartons are provided with an upstanding flange at the top, means for feeding a row of the cartons, a plunger and means for reciprocating the same, a plurality of stationary and movable gripping jaws on the plunger, means for moving the movable jaws into closed position to cooperate with the stationary jaws, the jaws defining channels between them when in open position to accommodate the flanged tops of a number of cartons sufficient to fill a crate into which the cartons are to be deposited, means for moving cartons directly from the feed row to position below the plunger without an intervening stop and with the flanges of the cartons located in the channels between the jaws, crate-transport means operative below the plunger and arranged to halt a crate in carton-receiving position below the plunger, crate-elevating means operative from below each crate when the crate is in carton-receiving position to thereby raise the crate to bring its open top toward the plunger, a slidable carton support located between the plunger and crate, and means for withdrawing the support to permit the plunger to descend and deposit the cartons held by it into the crate while the crate is maintained by its elevating means in an elevated position.

9. In an apparatus for depositing paper cartons into a crate, which cartons are provided with an upstanding flange at the top, means for feeding a row of the cartons, a plunger and means for reciprocating the same,

a plurality of stationary and movable gripping jaws on the plunger, means for moving the movable jaws into closed position to cooperate with the stationary jaws, the jaws defining channels between them when in open position to accommodate the flanged tops of a number of cartons sufficient to fill a crate into which the cartons are to be deposited, means for moving cartons directly from the feed row to position below the plunger without an intervening stop and with the flanges of the cartons located in the channels between the jaws, crate-transport means operative below the plunger and arranged to hold a crate in carton-receiving position below the plunger, crate-elevating means operative from below each crate when the crate is in carton-receiving position to thereby raise the crate to bring its open top toward the plunger, said crate-elevating means including stops for engagement with the ends of the elevated crate, one of the stops being operative to halt the movement of a succeeding carton, said elevating means also including a pivoted finger operative to locate the elevated crate in filling position, a slidable carton support located in between the plunger and crate, and means for withdrawing the support to permit the plunger to descend and deposit the cartons held by it into the crate while the crate is maintained by its elevating means in an elevating position.
